UNITED STATES PATENT OFFICE.

CLIFFORD D. BABCOCK, OF NEW YORK, N. Y., ASSIGNOR TO UNITED WIRELESS TELEGRAPH COMPANY, OF NEW YORK, N. Y., A CORPORATION OF MAINE.

SPACE TELEGRAPHY.

965,060.

Specification of Letters Patent. Patented July 19, 1910.
Application filed July 17, 1907. Serial No. 384,224.

To all whom it may concern:

Be it known that I, CLIFFORD D. BABCOCK, a citizen of the United States, and a resident of New York, in the county of New York and State of New York, have invented a new and useful Improvement in Space Telegraphy, of which the following is a specification.

My invention relates to apparatus for developing high frequency electrical oscillations for the telegraphic or telephonic transmission of intelligence by electromagnetic waves or for any other purposes for which such oscillations may be useful as, for example, the transmission of power, electrical dissociation of gases, etc.; and it relates more to an apparatus for developing electrical oscillations of high power.

The object of my invention is to provide an oscillation producer in which the sound of the electrical discharge may be muffled and free ventilation provided for the spark-gap, and by which any desired high and uniform spark frequency may be obtained while, at the same time, preserving the constants of the spark—i. e., its breakdown point and its point of cessation, thereby obtaining a constant and regular spark frequency and increasing the energy of radiation.

Other objects of my invention will hereinafter appear and will be more fully set forth.

With these objects in view my invention comprises spark-electrodes, one or both of which may be rotated at any desired speed, a source of electrical energy for creating a discharge between said electrodes, a source of gas, which may be air or any other suitable gas, under pressure, and means for creating a sudden flow of said gas under pressure across the gap between said electrodes during the time of said discharge.

The drawings which accompany and form a part of this specification represent several embodiments of my invention as applied to a space telegraph system, although it will be understood that the utility of my invention is not limited to space telegraphy and that said invention may be employed for producing electrical oscillations for any useful purpose.

In the drawings Figure 1 represents partly in diagram and partly in section one arrangement of apparatus and circuits illus-

trating one embodiment of my invention applied to a space telegraph transmitting system. Fig. 1^a is a section on line a—a of Fig. 1 looking in the direction of the arrow. Figs. 2, 3, 4 and 5 are representations of space telegraph systems similar to Fig. 1 and illustrating modifications of the apparatus and circuits shown in Fig. 1.

In the figures, G is a suitable source of energy herein shown as an alternating current generator.

M is a transformer, preferably of the step-up type.

I₁ and I₂ respectively are the primary and secondary windings of the transformer M.

A is an antenna earthed at E through a portion of the inductance L.

C is a condenser.

K is a key.

k is a spring contact coöperating with the back contact of the key K.

B is a source of electrical energy, herein shown as a battery.

In Figs. 1, 2, 3 and 5, 14 represents a vessel or casing having an air tight cover 15. The conducting property of the vessel 14 may be opposite to that of the cover 15 and, as shown, the vessel is made of conducting material and the cover of insulating material. Spark electrodes of any suitable construction may be inclosed within said vessel and connected with a source of electrical energy and an oscillation circuit. In the present instance the electrodes are shown in Figs. 1 and 4 as consisting of two turbines

and in Fig. 3 as consisting of one turbine and its nozzles, although as shown in Fig. 2, both electrodes may be stationary. In Fig. 1 the turbines 16 and 17 are provided with spark points 18 and 19 respectively. The electrode 16, 18, is connected with the secondary I₂ by the lead b, c, e, and the electrode 17, 19 is connected to said secondary by the lead terminating at the binding post d', which is in conductive connection with said electrode 17, 19, through the metal of the casing 14. The electrode 16, 18 may be

adjustably connected to a point on the inductance L by the lead e, c, and the electrode 17, 19 may be connected with one terminal of the condenser C by the lead terminating at the binding post d. When so connected the condenser may discharge across the gap

between said electrodes when the potential

17, 19 may be connected with one terminal of the condenser C by the lead terminating at the binding post d. When so connected the condenser may discharge across the gap

between said electrodes when the potential

to which the condenser is charged is sufficient to break down the dielectric between the electrodes, and thereby create oscillations in the oscillation circuit 19 of C L c 18.

5 It will suffice in systems employing small amounts of power to use spark-electrodes consisting of stationary metallic bodies, generally spherical in form, but when large amounts of power are employed, as in long 10 distance space telegraph systems, many difficulties arise which prevent the use of such simple discharger and which require the employment of more elaborate apparatus. One 15 of these difficulties consists in the creation of an electric arc in the spark-gap which tends to short-circuit the prime source of energy and thereby prevent the charging of the condenser to its full capacity, and which renders such sparking as does take place 20 irregular in action. In such high power systems, it is necessary also to employ means for muffling the sound of the spark and at the same time to provide for the renewal of the atmosphere in which said spark takes 25 place. I am aware that it has been proposed to employ mufflers for spark gaps, to create the spark in an atmosphere of compressed gas and to employ slowly rotating spheres as spark-electrodes; but so far as I 30 am aware it is novel to create the spark in a muffler having a constantly circulating atmosphere of gas under high pressure, whereby the insulation of the gap may be maintained at a high point owing to the constant 35 clearing out of minute metallic particles torn off the electrodes and the expulsion of the vitiated gas; and to provide sudden and excessive exacerbations of said gas under high pressure during the time of 40 the production of the spark, whereby arcing across the electrodes may be prevented.

While of course the means hereinafter described for creating a spark in a muffler having a constantly circulating atmosphere 45 of gas under high pressure and for creating a sudden inrush of such gas during the sparking periods may be employed in connection with any type of spark electrodes, I prefer as shown in Figs. 1, 3, 4 and 5 to 50 employ said means with electrodes one or both of which is rotated at any suitable speed so as to increase the spark-frequency of the electrical oscillations and thereby increase the energy developed in a given unit 55 of time.

While various means may be used for effecting the foregoing results, I shall herein describe one specific and very effective arrangement of apparatus for the purpose of 60 more fully disclosing my invention, but not with the intention of limiting myself to such apparatus. For this purpose, referring to Fig. 1, 4 represents any suitable type of air or gas compressor, the inlet pipe 5 of which 65 may be provided with a screen 6 for remov-

ing any foreign matter from the air or gas which is drawn into the compressor. 1 represents a reservoir connected with said compressor by the pipe 4' and provided with a drain-pipe 3 and a pressure gage 2. The 70 operation of the compressor may be controlled by any of the well known automatic devices for maintaining the gas in the reservoir at a constant high pressure. The desiccating chamber 8 containing unslaked lime, calcium carbide, or any other suitable desiccating substance, may be inserted between the outlet pipe 4'' of the reservoir and the pipe 8' which leads into the muffling chamber 14, 15. 80

9, 9' are pressure regulating valves herein shown as electromagnetically operated. In the present instance, the energization of the coils of the electro-magnets 10, 10' causes the partial rotation of the armatures 11, 11' 85 against the tension of the springs which hold said armatures against the stops 12, 12' respectively, the movement of the armatures being limited by the stops 13, 13'. As shown in Fig. 1, conventionally, the armatures 11, 11' 90 are connected with and operate the valves 9, 9'. Such devices are well known and need not be further described.

While the valves 9, 9' may be set so as to close the passages 8', 26 until the closure of the primary power circuit or shortly before such closure, I prefer to set said valves so that a constant circulation of gas under high pressure is maintained in the muffler. For instance, the valve 9' may normally be 95 slightly open and the valve 9 may normally be opened to a greater degree, so that a pressure of, say, seventy pounds per square inch is maintained in the muffler. Then in the present instance, by the closure of the circuit of the battery B by the coöperation of the back contact of the key K with the spring k, the valves 9, 9' will be simultaneously opened thereby permitting a sudden and excessive inrush of air or gas into the 100 muffler. For example, if the pressure in the reservoir is maintained at 114.25 pounds per square inch, the effective pressure in the muffler will be 44.25 pounds per square inch when the pressure in the muffler is that 105 above set forth, and such effective pressure will prevent any arcing that otherwise might take place in the gap while at the same time preserving the constants of the spark and causing the same to start and stop much 110 more suddenly than otherwise. By virtue of the maintenance of the relatively high gas pressure in the muffler, the dielectric strength of the spark-gap is increased and the ventilation caused by the above mentioned circulation still further maintains such dielectric strength by reducing the heat dissipation in the muffler. It will be obvious 115 from the foregoing that the valve 9 may be omitted. For the purpose of still further 120

5 preventing arcing where large amounts of energy are employed, as well as for increasing the spark-frequency of the electrical oscillations, I prefer to employ, with the apparatus above described, spark electrodes, one or both of which may be rotated. One example of such rotating electrodes is shown in Fig. 1, in which 16, 17 represent turbines operated by the compressed gas passing 10 through the oppositely directed jets 20, 21, whereby the turbines are caused to rotate in opposite directions at any desired speed. Thus for example if the pressure maintained in the muffler is 70 pounds per square inch 15 and that maintained in the reservoir is 114.25 pounds per square inch, so that the effective pressure at the jets is 44.25 pounds per square inch, there will be obtained with ten inch disk turbines a speed of approxi- 20 mately 1326 revolutions per second, the velocity of inrush of air into a vacuum, equal to an effective air pressure of 14.75 pounds per square inch, being taken as 1151 feet per second. Each disk 16, 17 may carry 25 as many spark-points of any desired shape as desired, and if, as shown in Fig. 1, one disk carries twenty points and the other a single point we should get a spark frequency of about 26000 per second, provided the disk 30 17 carrying said single point were stationary, and a spark frequency of about 52,000 if said disk 17 rotates at the same speed as the disk 16 and in the opposite direction.

One of the disks, herein shown as the disk 35 16, may be adjustable with respect to the other by the nuts and lock nuts 22. In this case the jet 20 may as shown be elongated to allow for such adjustment.

40' represents a window through which 40 the operation of the spark may be observed. 23 represents a wiper of any suitable construction whereby the surfaces of the spark points may be cleaned. As shown, 23 consists of a bar of any suitable material at- 45 tached to the stem 24 which may be pushed through the wall of the casing 14 until said bar is in the space between the points 18, 19, and then turned by the handle 25 as indicated in Fig. 1^a, so that the points 18 pass 50 over the upper side of the wiper and the point or points 19 passes under the lower side thereof, until the surfaces of said points are cleaned, whereupon the stem 24 may be withdrawn to the position shown in Fig. 1.

55 In Fig. 2 I have shown a modification, in which as in Fig. 1, the pressure of the gas in the reservoir (not shown but connected to the inlet pipe 8' as in Fig. 1) is maintained higher than in the muffler, the difference in pressure depending upon the setting of the valve 9'. By this arrangement I may obtain a spark in a gas under relatively high pressure, while the difference in the pressure maintained in the reservoir and in the 60 muffler insures the ventilation of the latter.

One electrode may be the end 27 of the inlet pipe 8' and the other, a disk 29 maintained at an angle other than 90 degrees with the stem 29, which is manually rotatable by means of the head 28 for adjusting the 70 length of the gap. In Fig. 2, as in Figs. 3, 4 and 5, X X' represent the electromagnetic actuating devices for the valves 9, 9' which are shown in detail in Fig. 1 at 10, 11, 12, 13.

75 In Fig. 3, the inlet 8' is branched into two pipes 31, 32, terminating into horizontally adjustable jets 33, 34, respectively, which are directed so as to mutually assist in the rotation of the turbine 30, the vanes of said 80 turbine and said jets constituting the spark electrodes. In this case the spark-gap will be a multiple gap.

In Fig. 4, I have shown a further modification in which the disks 38, 39 are driven in the same direction—i. e., both clockwise or both counter-clockwise, so that the spark points 40, 41 pass each other at the point S in opposite directions at a high rate. In this figure, the casing 36 may be of insulating material and the cover 37 of conducting or other material, as shown. e, e' represent the points of connection of the electrodes 39, 41 and 38, 40 with the secondary of the transformer M and with the oscillation circuit.

90 Fig. 5 shows another modification in which a gas repulsion motor 42 is employed as a rotating electrode for the spark-gap, of which the other electrode is shown as the 100 normally stationary and adjustable rod 43.

95 It will be observed that in all the forms illustrated, upon the closing of the key K, a sudden increase in pressure, and therefore of the dielectric strength, is produced between the electrodes, and simultaneously a sudden rotative impulse is imparted to the movable element, or elements, which adds to the effect of the increase in pressure in producing a sharp and well-defined spark 110 so essential to an efficient apparatus of this nature.

115 It will be obvious that the apparatus and circuits hereinbefore specifically described may be subjected to a wide range of variation without departing from the principle of my invention.

I claim:

1. In an oscillation producer, a vessel; electrodes, one of which is provided with a plurality of points, in said vessel, and one of which is movable relative to the other; a source of gas under pressure; means for producing an electrical discharge between said electrodes; and automatic means for 120 creating a sudden flow of said gas under pressure, into said vessel during said electrical discharge, and simultaneously imparting motion to said movable electrode, substantially as described. 130

2. In an oscillation producer, a vessel, electrodes in said vessel, means maintaining a constant circulation of gas under pressure in said vessel, a source of electrical energy for said electrodes, and means for creating a sudden and excessive increase in said circulation during the application of the electromotive force from said source to said electrodes.
- 10 3. In an oscillation producer, a vessel provided with a movable spark-gap, and means for creating a sudden inrush of gas under pressure across said gap during the discharging periods thereof, and simultaneously imparting motion to one of the members of said gap.
- 15 4. In an oscillation producer, a vessel provided with a moving spark-gap, a source of gas under pressure, means connecting said source with said vessel, a source of electrical energy for said spark-gap, and means whereby a sudden inrush of said gas under pressure into said vessel is created when said gap is energized, and motion is simultaneously imparted to said gap.
- 20 5. In an oscillation producer, a vessel provided with a moving spark-gap, a source of gas under pressure adapted to move said gap, a pipe connecting said source with said vessel, a source of electrical energy for said spark-gap, an electrically operated valve in said pipe, and means for operating said valve during the energization of said gap.
- 25 6. In an oscillation producer, a vessel provided with a moving spark-gap, a source of gas under pressure adapted to move said gap, a pipe connecting said source with said vessel, a source of electrical energy for said spark-gap, an outlet pipe for said vessel, an electrically operated valve in said outlet pipe, and means for operating said valve during the energization of said gap.
- 30 7. In an oscillation producer, two electrodes, and automatic means for rotating and simultaneously increasing the dielectric strength between the same during the period of discharge, substantially as described.
- 35 8. In an oscillation producer, two electrodes; a plurality of spark points on one of said electrodes; and means for rotating said electrodes and simultaneously increasing the strength of the dielectric between the same during the discharge, substantially as described.
- 40 9. An oscillation producer provided with a spark electrode consisting of a turbine wheel, adapted to receive air under pressure while constituting one terminal of a spark gap; and means to deliver said air to said electrodes, substantially as described.
- 45 10. In an oscillation producer, two spark electrodes, each consisting of a turbine wheel, adapted to receive air under pressure while the spark is passing and means to deliver said air to said electrodes, substantially as described.
- 50 11. In an oscillation producer, two spark electrodes, each consisting of a turbine wheel, and means for rotating the same in opposite directions.
- 55 12. In an oscillation producer, a vessel, two electrodes, each consisting of a turbine wheel, a source of gas under pressure, a source of electrical energy for said electrodes, and means for creating a sudden inrush of said gas in said vessel and against said turbine during the application of said electrical energy to said electrodes.
- 60 13. In an oscillation producer, spark-electrodes consisting of turbine wheels, each adapted to receive air under pressure while the spark is passing; means for rotating one of said electrodes, means for delivering air thereto; and means located between said electrodes for cleaning the surface thereof during rotation.
- 65 14. In an oscillation producer, a casing; spark-electrodes in said casing; means for rotating the same; and means located partly in and partly outside of said casing for cleaning the surfaces of said electrodes during rotation, said last mentioned means comprising a handle, a stem projecting through the casing, and a wiper of insulating material adapted to be rotated by said stem and brought into contact with said electrodes, substantially as described.
- 70 15. In a wireless telegraph transmitter the combination of two disks, means for rapidly rotating the disks in opposite directions, studs on the adjacent faces of the disks, and an oscillation circuit connected to the disks.
- 75 16. In a wireless telegraph transmitter the combination of two parallel disks, means for rapidly rotating the disks in opposite directions, studs on the adjacent faces of the disks, and an oscillation circuit connected to the disks.
- In testimony whereof, I have hereunto subscribed my name this 2nd day of July 1907.
